DESIGN FOR A WALL PLAQUE

Wade H. Darby, McDowell, Va.

Application February 20, 1939, Serial No. 83,122

Term of patent 7 years

To all whom it may concern:

Be it known that I, Wade H. Darby, a citizen of the United States of America, residing at McDowell, county of Highland, and State of Virginia, have invented a new, original, and ornamental Design for a Wall Plaque, of which the following is a specification, reference being had to the accompanying drawing, forming part thereof, wherein:

I claim:

The ornamental design for a wall plaque, as shown.

WADE H. DARBY.
